UNITED STATES PATENT OFFICE.

GEORGE S. LEINER, OF NEW ROCHELLE, AND CHARLES A. BERNSTEIN, OF NEW YORK, N. Y.

BRUSH.

Application filed December 10, 1923. Serial No. 679,566.

To all whom it may concern:

Be it known that we, GEORGE S. LEINER and CHARLES A. BERNSTEIN, citizens of the United States, and residents of New Ro-

chelle, county of Westchester, and State of New York, and of the city, county, and State of New York, respectively, have invented a certain new and useful Improvement in Brushes, of which the following is

10 a specification.

The object of this invention is to provide a brush used for cleaning purposes, scrubbing, polishing surfaces, washing of windows and the like, which will be of strong 15 and sturdy construction, capable of standing considerable hard usage, and which will, by reason of its construction be particularly adapted for the nature of the work to which it may be put.

20 With these objects and such other objects as may hereinafter appear, we have devised the particular arrangement of parts set forth below and pointed out in the claims appended hereto.

25 Reference is to be had to the accompanying drawing, forming a part thereof in which—

Figure 1 is a plan view of our improved brush, parts being broken away and in section, to disclose construction,

30 Figure 2 is a sectional view on the line 2—2 of Figure 1, looking in the direction of the arrows.

Throughout the various views of the 35 drawings, similar reference characters designate similar parts.

In the accompanying drawing, 1 indicates the wire core of the brush. This is preferably constructed of a single section of twisted wires made in the form of a continuous 40 loop. The bristles or other material utilized 2 are secured to the wire core in a customary manner by holding the same between the twists of the wire strands which 45 make up the core 1.

At a substantially central point the twisted wire core 1 is bent to form a connecting bar 3 which has its end 4 permanently joined to the end of the wire core as at 50 5 by welding or any other method. The weld is preferably formed by interlacing or overlapping the two wires from bar 3 and the two wires from the other end of core 1, and then welding, whereby the ends 55 are in effect both spliced and welded, thus

forming a union stronger than either pair of wires forming it. This forms the wire core as before mentioned in a continuous loop.

The clamp which receives the handle is disclosed at 6 and the same is provided with a tubular portion 7 at its end through which the cross bar 3 of the wire passes. The cross bar serves as a bearing for a clamp to be described. The clamp is provided with two jaws 8 and 9 which project from the tubular portion 7 and which are connected by a clamping screw 10 and the finger operated nut 10' to enable them to be drawn together to clamp any ordinary 70 wooden handle 11 between them.

The shape or design of the twisted wire core holding the bristles or other material is so formed or constructed that the handle connector or clamp 6 is placed in such a 75 position on the brush, that it may turn over or oscillate to the opposite side of the brush. This permits the brush to be utilized on either side without removing the handle from the clamp or handle connector.

This connector in which the handle is attached, by being able to oscillate on the axle of the wire core, allows the brush to lie flat against any surface, regardless of the angle the handle is held, and without 85 allowing any part or end of the wire core of the brush or any metal part to come in contact with the surface being cleaned or polished.

From the foregoing it will be apparent 90 that the simple construction of the brush makes it a strong and sturdy article capable of hard usage. The welded joint at 5 for the ends of the wire core work 1 forms said core into a continuous unbreakable 95 loop.

The convenience of being able to use both top and bottom sides of the brush to advantage without removing handle from the handle connector is also apparent.

The lower cost of manufacture is also 100 obvious, since the component parts of wire and bristles are twisted together in one operation, thereby forming the body, core and frame work of the brush, without the need 105 of any binding, adhesive or other material, or any other operation to secure or apply the bristles to the frame or core on which the handle connector 6 is attached.

From the foregoing it is obvious that our 110

invention is not to be restricted to the exact embodiment shown but is broad enough to cover all structures, shapes or designs coming within the scope of the annexed claims.

5. What we claim is:

1. A brush formed of a pair of wires twisted together, with bristles held between the twisted wires, the end portions of the twisted wires both being bent inwardly to ward the center of the brush, one end portion being further bent to form a bearing, the four ends of the two wire portions being overlapped and welded to form a union immediately adjacent the said bearing, the union being at the bend connecting the bearing with the other wire portion, a clamping element rotatably mounted on the bearing, and a handle carried by said clamping element.
10. 2. A brush formed of wires twisted together with bristles permanently held be-

tween the twisted wires, the end portions of the twisted wires being bent inwardly toward the center of the brush, one of the end portions being further bent to form a bearing, the four ends of the two wire portions being overlapped and welded together so that the weld is immediately adjacent the bearing, a tubular sleeve surrounding the bearing and rotatable thereon, provided with a pair of semi-cylindrical gripping jaws, a threaded element extending directly through said jaws about midway of their length, and a finger operated nut cooperating with the threaded element for drawing the jaws together for detachably gripping a handle therebetween.

Signed at the city, county and State of New York, this 30th day of November, 1923.

GEORGE S. LEINER.
CHAS. A. BERNSTEIN.
